UNITED STATES PATENT OFFICE.

IRENE H. OVINGTON, OF BROOKLYN, NEW YORK.

DESIGN FOR A BED-PAN.

SPECIFICATION forming part of Design No. 18,958, dated March 12, 1889.

Application filed October 12, 1888. Serial No. 287,965. Term of patent 7 years.

To all whom it may concern:

Be it known that I, IRENE H. OVINGTON, a citizen of the United States, residing in Brooklyn, Kings county, State of New York, have 5 invented and produced a new and original Design for a Bed-Pan, of which the following is a specification, reference being had to the accompanying drawings, forming part thereof.

Figure 1 is a plan view. Fig. 2 is a side view. Fig. 3 is a cross-section.

The leading features of my design consist in the indentations A shown in Fig. 1 and the pointed shoe shape shown in Fig. 2.

From the point B, Figs. 1 and 2, there is 15 first a depression to C, then a gradual elevation to D on the top of sides. There is a cover from the point B extending to C C, which is concave and meeting at a point. B forms a triangular cover, E, over the front

part of the bed-pan, the back part being entirely open from the point C to D.

From the point B, in both Figs. 1 and 2, there is a gradual swell on both sides to the point C', and from this point a sharp curve to D'. From D to D' the form assumes a section of a circle. The bottom outline, from B to H, has a shoe shape, with an elevated toe curved upward from the point F.

What I claim is—

The design for a bed-pan herein shown and 30 described, the same comprising the concave covering E, the depression A, the circular form D' D', and the shoe-shaped outline B C D H F.

IRENE H. OVINGTON.
